UNITED STATES PATENT OFFICE.

PHILIP C. WENTWORTH, OF PROVIDENCE, RHODE ISLAND.

TWISTER TRAVELER.

Application filed July 21, 1926. Serial No. 123,872.

This invention relates to self-lubricating twisting travelers, and involves certain changes in the construction of the travelers shown in my prior Patent No. 1,415,072 granted May 9, 1922, to which reference is made as containing a full discussion of the problem involved in this art.

According to my present invention, the lubricant collecting area of the traveler is formed as a pocket or recess pressed out of the ring-contacting face of the traveler. This pocket or recess acts as a trap for the lubricating grease with which the twisting ring is smeared. During the run of the spindle, the contact of the traveler with the ring mechanically transfers particles of such grease to the traveler, and as the traveler becomes heated, the lubricant thus transferred to it melts and flows out of said pocket towards the traveler foot where the wear is greatest and the need of proper lubrication most essential.

In the accompanying drawings I have shown a form of twister traveler which well illustrates the principles involved. In these drawings:

Fig. 1 is an elevation of a traveler, in accordance with my invention, applied to a twisting ring.

Figs. 2 and 3 are perspectives of said traveler, and

Fig. 4 is a longitudinal section through the traveler.

I have indicated at 1 a twisting traveler of standard type, and at 2 a portion of a vertical twisting ring upon which the traveler rotates.

The ring contacting face of the traveler, between its ends, is pressed out to provide a

lubricant recess or pocket 3 of such size and shape as may be found most efficient, depending upon the size and weight of the traveler.

In practice, the inner face of the twisting ring is smeared with a hard, non-fluid, lubricating grease. During the run of the spindle, the traveler contacts the inner face of the ring and mechanically transfers to itself particles of the lubricating grease, and these particles are caught or collected in the pocket or recess 3 pressed out of the body of the traveler itself.

The lubricant thus transferred to the traveler melts under the heat developed between the traveler and the ring in the operation of the traveler and flows downwardly toward the traveler foot 4 where the need for adequate lubrication is most pronounced.

By pressing or indenting the pocket from the metal of the traveler, I avoid the physical removal of any metal, with resultant variation in weight of the traveler, as well as permitting convenient production of the travelers in commercial quantities.

Various other modifications in structure and arrangement as come within the spirit of my invention may obviously be made within the limits of the appended claim.

What I therefore claim and desire to secure by Letters Patent is:

A twister traveler for use on a vertical twisting ring comprising a member presenting a top flange, a bottom foot, and a back connecting said flange and foot, said back being pressed out to provide a lubricant pocket terminating short of the traveler foot. 75

In testimony whereof I affix my signature.

PHILIP C. WENTWORTH.
